[57] CLAIM

The ornamental design for a dice game accessory, as shown and described.

DESCRIPTION

FIG. 1 is a top, side perspective view of a dice game accessory showing my new design;

FIG. 2 is a top plan view thereof;

FIG. 3 is a bottom plan view thereof; and,

FIG. 4 is a side elevational view thereof, all other side elevational views being identical due to the symmetrical nature of the design.
